George L. Slater.

By his Attorney *Chas. H. Fowler*

UNITED STATES PATENT OFFICE.

GEORGE L. SLATER, OF BUCHANAN, MICHIGAN, ASSIGNOR OF ONE-HALF
TO JOHN E. BARNES, OF SAME PLACE.

TABLE-LEAF SUPPORT.

SPECIFICATION forming part of Letters Patent No. 357,506, dated February 8, 1887.

Application filed February 9, 1886. Serial No. 191,384. (Model.)

To all whom it may concern:

Be it known that I, GEORGE L. SLATER, a citizen of the United States, residing at Buchanan, in the county of Berrien and State of Michigan, have invented certain new and useful Improvements in Table-Leaf Supports; and I do hereby declare that the following is a full, clear, and exact description of the same, reference being had to the annexed drawings, 10 making a part of this specification, and to the letters and figures of reference marked thereon.

Figure 1 of the drawings is a perspective view of a portion of a folding table, showing 15 the leaf extended and supported in such position by my improved device. Fig. 2 are detail views of the latch device and lower end of the brace-rod which engages therewith.

The present invention has relation to that 20 class of table-leaf supports consisting of a brace-rod connected at one end to the under side of the table-leaf and at its opposite end to a device secured to the rail or frame of the table, which will enable the leaf to be either 25 let down or supported in an extended position.

The object of the invention is to improve 30 the construction of the above-mentioned class of devices, whereby greater certainty in its action is obtained, more readily and conveniently operated, and possessing increased strength as a support to the leaf. These objects I attain 35 by the construction substantially as shown in the drawings, and hereinafter described and claimed.

In the accompanying drawings, A represents the table, and B one of the leaves hinged thereto, said table being of any of the usual forms and supported on the ordinary frame 40 or rails *a*, to which are secured the legs *b*.

My invention being equally applicable to all classes of tables having folding leaves, I have shown in the drawings only one form in order to fully illustrate the application of the 45 invention.

To the under side of the table-leaf B is attached, by a universal joint, one end of a brace-

rod, C, which may be either round, square, or other form, as found desirable. The most simple and effective universal joint for the 50 purpose is the ball-and-socket joint, which I have shown at *c*, although any universal joint may be used that will admit of the brace-rod turning on its axis, and also on the arc of a circle, when the table-leaf is raised or lowered. 55

The brace-rod C is provided, at or near its upper end, with a thumb-piece, *d*, for turning it, and at its opposite end it is provided with a head, *e*, and shoulders *f*, so that when in the position shown in Fig. 1 the shoulders will 60 hold the rod extended to support the table-leaf. Secured to the frame or rail *a* is a latch or holding device, D, preferably consisting of two spring-arms, *g*, with shoulders *h* at their ends. 65

When the table-leaf is extended, as shown in Fig. 1, and it is desired to let said leaf down, the brace-rod C is turned by means of the thumb-piece *d* until at right angles to its former position, the spring-arms *g* spreading 70 for this purpose. After turning the rod as above described, as soon as the cams *i* strike the spring-arms *g*, the rod turns partly over, allowing the cams to pass between the arms without spreading them. In raising the leaf 75 B the cams themselves striking against the inner sides of the spring-arms will automatically turn the rod to allow the end of the same to be again held by the latch D.

I do not desire to be understood as confining myself to the specified construction of the latch or holding device, as it may be variously modified without departing from the spirit of my invention. 80

Having now fully described my invention, 85 what I claim as new, and desire to secure by Letters Patent, is—

1. A table-leaf support having projections at one end to engage a slotted device, as D, secured to the table-frame and having a universal-joint connection with the leaf, whereby the engagement between the support and table may be broken at will by turning the support upon its axis, as set forth. 90

2. A table-leaf support consisting of a latch or spring holding device, D, secured to the frame or rail of the table, and a brace-rod connected at one end to the table-leaf by a universal joint, and at its opposite end provided with cam-shoulders and a head, substantially as and for the purpose specified.

In testimony that I claim the above I have hereunto subscribed my name in the presence of two witnesses.

GEORGE L. SLATER.
